(57) **ABSTRACT**

A modular lighting assembly uses LED banks as the light sources. The assembly allows the power supply and LED banks to be independently replaced. The assembly uses a power supply that is separated from the LED banks and electrically connected to the LED banks with a plug connector that may be unplugged and plugged back in to allow the power supply or LED bank to be independently and readily replaced. The assembly provides for easy replacement of the different components of the assembly. One feature that makes the components easier to replace is that the light modules and/or the power supply may be carried by the housing that is removable from the base mount that is secured to a mounting structure such as a wall or ceiling.

LIGHTING ASSEMBLY

CROSS REFERENCE TO RELATED
APPLICATIONS

This application is a continuation application claiming priority to U.S. patent application Ser. No. 16/742,838 filed Jan. 14, 2020, U.S. Pat. No. 11,204,154, which is a continuation application claiming priority to U.S. patent application Ser. No. 15/455,872 filed Mar. 10, 2017, which is a continuation application claiming priority to U.S. patent application Ser. No. 13/271,115 filed Oct. 11, 2011, U.S. Pat. No. 9,625,139 issued Apr. 18, 2017, which claims the benefit of U.S. Provisional Patent Application No. 61/391,608 filed Oct. 9, 2010; the disclosures of each are incorporated herein by reference.

BACKGROUND OF THE DISCLOSURE

1. Technical Field

The disclosure generally relates to LED lighting devices and, more particularly, to modular LED lighting units that may be uniquely configured by the user at the location where the lighting is desired.

2. Background Information

Although the benefits of upgrading traditional lighting to efficient lighting based on light emitting diodes (LEDs) is known, additional LED lighting configurations are desired in the marketplace.

SUMMARY OF THE DISCLOSURE

The disclosure provides a modular lighting assembly using LED banks as the light sources. The assembly allows the power supply and LED banks to be independently replaced. The assembly uses a power supply that is separated from the LED banks and electrically connected to the LED banks with a plug connector that may be unplugged and plugged back in to allow the power supply or LED bank to be independently and readily replaced.

The disclosure provides an assembly that provides for easy replacement of the different components of the assembly. One feature that makes the components easier to replace is that the light modules and/or the power supply may be carried by the housing that is removable from the base mount that is secured to a mounting structure such as a wall or ceiling. This configuration allows the replacement to occur at ground level rather than requiring the worker to be positioned up on a ladder.

The disclosure also provides a mount that allows the power supply and LED banks to be placed at different locations and allows for the LED banks and power supplies to be removed and replaced.

The mount allows the light generated from the system to be directed in different directions based on the installation position of the LED banks. The housing that mounts the light modules is angled at different directions with respect to its base to cast the light generated by the light modules in desired directions.

The disclosure also provides a lighting assembly that has a low power mode that may be activated to reduce power consumption. The low power mode may be activated manually, automatically, or remotely.

2

The disclosure also provides a lighting assembly that may be used in underground applications including underground train systems.

The disclosure provides a LED lighting assembly that may be powered from a 480V, three phase input.

The disclosure provides a lighting assembly with improved efficiency.

BRIEF DESCRIPTION OF THE DRAWINGS

10 FIG. 1 is perspective view of an exemplary modular light assembly.

15 FIG. 2 is an exploded perspective view of the assembly of FIG. 1.

15 FIG. 3 is an exploded perspective view showing how the power supply and LED banks interact with the mount.

20 FIG. 4 is a view similar to FIG. 1 showing an alternative configuration for the modular light and mount.

Similar numbers refer to similar parts throughout the specification.

DETAILED DESCRIPTION OF THE
DISCLOSURE

25 An exemplary configuration of a lighting assembly is indicated generally by the numeral 2 in the accompanying drawings. Lighting assembly 2 may be used in a wide variety of environments and is particularly configured for underground utility or underground transportation applications. Assembly 2 may be used for tunnel lighting, subways, parking garages, harsh-environment conditions, architectural and industrial operations including petroleum, mining, and power generation. Assembly 2 is configured to function in damp environments and is configured to be impervious to 30 dust such as steel dust and corrosion. Assembly 2 is configured to have an operating temperature in the general range of -20° to 50° C.

35 Assembly 2 uses a plurality of light emitting diode (LED) light sources grouped to function as a single light source 40 referred to herein as an LED banks or LED light module 4. Module 4 provides the desired light from assembly 2. Assembly 2 allows the individual elements of the assembly to be replaced and reconfigured as desired by the end user. Assembly 2 allows the user to select the type of light module 4 used at different locations. For example, the user may install large and small light modules 4, different color light modules 4, light modules 4 having different shapes, or light modules 4 of differing lumen output. The LEDs are configured with an automotive-grade polycarbonate lens assembly. The injection molded components are low smoke, zero 45 halogen (LSZH). Each module 4 includes a die-cast aluminum heat sink. Each module 4 has a LED Driver operating voltage of 100-277 VAC, 480 VAC. Alternate high-voltage AC/DC input may be provided. The power consumption for one exemplary configuration is 60 Watts. The LEDs may be high-output bright white LED's (~4700K). The LEDs have a rated life of 70% lumen maintenance at 50,000 hours. Modules 4 use the proprietary, precision Opticlear™ Engine 50 to maximize light distribution to target area while minimizing glare.

55 Assembly 2 generally includes at least one LED module 4, a mount 6, and a power supply 10. Mount 6 is configured to carry at least one module 4 and a power supply 10. A plurality of identical or different light modules 4 may be carried by mount 6. Mount 6 may be provided in different configurations to direct the light produced by assembly 2 in 60 different directions. Each module 4 and supply 10 may be

readily mounted and dismounted to mount **6** and may be connected and disconnected from each other to allow each individual element to be replaced as needed.

Power supply **10** transforms the alternating current from commonly available electrical power sources such as 110V or 220V or a high voltage source such as 480V-three phase, to a low voltage direct current power supply that is delivered to module **4** with a supply cord **12**. Supply cord **12** (shown disconnected in FIG. 1 and connected in FIG. 4), power supply **10**, and/or module **4** include connectors **14** configured to allow cord **12** to be readily connected and disconnected from supply **10** and/or module **4**. Connectors **14** may be waterproof and locking. A waterproof IP67 connector may be used. As shown in FIG. 4, modules **4** may be connected together with a secondary electrical connector **16** such that the electrical supply flows through one module **4A** to the second module **4B**. Alternatively, power supply **10** may include multiple outlets **18** with an independent supply cord **12** used with each module **4**. Power supply **10** may include a plug that allows assembly **2** to be plugged into the available electrical source or assembly **2** may be hard wired into the electrical source. Power supply **10** may be configured to function with a wide range of input voltages and may be configured to withstand power spikes. In the exemplary configuration, power supply **10** outputs a 24V to each supply cord **12**. Power supply **10** may be double fused.

Assembly **2** may be provided with a low power feature that may be activated to reduce the amount of power consumed by assembly **2**. In one configuration, the low power mode reduces power consumption by 75 percent. The low power mode may be activated and deactivated with a button or switch on power supply **10**. Other configurations allow the low power mode to be activated or deactivated remotely through a wireless connection, through a computer network connection such as an Internet connection, and/or through a powerline network. These activation methods also may be used to turn assembly **2** on and off. Communication between power supply **10** and the controlling device (which may be a computer or a timer) may be through a computer network such as the Internet or an intranet, through a telephone network, through a wireless communication channel, or through any other suitable communication channel.

Mount **6** includes a base **20** and a housing **22**. Base **20** is configured to be secured to a structure such as a wall or ceiling while housing **22** carries module **4** or modules **4**. Modules **4** may be secured to housing **22** with connectors, a snap fit connection, or the like. Housing **22** defines an opening for each bank of LEDs in module **4**. In other configurations, housing **22** is configured to carry or at least cover power supply **10**. Housing **22** is readily removably from base **20** so that module **4**, modules **4**, or supply **10** may be replaced, reconfigured, or serviced. When module **4** is to be replaced, module **4** is unplugged from supply **10** and housing **22** and module **4** are removed together so that the replacement module **4** may be inserted into housing **22** in a location separate from the location where base **20** remains mounted.

Housing **22** may be angled up, down, left, right, or parallel with respect to base **20**. When housing **22** carries multiple modules **4**, housing **22** may be configured to hold modules **4** at different angles with respect to base plate **28**. In the exemplary configuration, housing **22** is angled down with respect to base **20** such that the light produced by module **4** or modules **4** is angled down. As such, when base **20** is mounted to a vertical surface such as a wall, the light produced by assembly **2** is angled down toward the floor. Also in the exemplary configuration, the center of housing

22 is taller than the ends of housing **22** so that the two different light modules **4** carried by housing **22** are angled away from each other.

Housing **22** may define a plurality of openings to allow air to circulate around module **4**, modules **4**, and power supply **10**.

Base **20** includes a generally flat base plate **28** that defines a plurality of mounting holes **30** that allow base **20** to be secured to a wide variety of surfaces with a wide variety of connectors. Each mounting hole is defined by a portion of plate **28** that projects rearwardly from a planar rear surface portion of plate **28**. Base plate **28** has a first end **32**, a second end **34**, an upper edge **36**, and a lower edge **38**. Channels are defined along upper and lower edges **36** and **38** with lips **40** and **42**, respectively.

Flanges **44** projecting from housing **22** are sized to slide within these channels between lips **40/42** and base plate **28** to retain housing **22** with respect to base **20**. Power supply **10** includes its own flanges **46** that project from a power supply mounting plate **48** that mounts power supply **10** to base in the same manner. Flanges **44/46** may be freely slidable within the channels or may be tapered to allow for easy insertion and frictional locking within the channels. The frictional locking occurs when the tip-to-tip distance from flange **44** to the opposite flange **44** is essentially the same dimension—or just smaller than—the dimension from the inside of one channel to the inside of the other channel. FIGS. 2 and 3 depict tapered ends on flanges **44** while FIG. 4 depicts rounded ends. Flanges **44** also may be frictionally pinched by being slightly thicker than the channels.

Power supply **10** may be connected to base **20** by sliding flanges **46** into the open end of the channels behinds lips **40/42** at second end **34** of base **20**. A stop **50** projects forward from base plate **28**. Power supply **10** abuts stop **50** when in the proper position. A connector, such as a screw or bolt, may be used to secure power supply **10** in place. Supply cord **12** also holds power supply **10** in place. Alternatively, flanges **46** may be configured to lock into the channels with friction fits or snap fits. In other configurations, power supply **10** is mounted within and carried by housing **22**.

Flanges **44** may be continuous such that housing **22** is slid into the channels through first end **32** in the same manner as power supply **10**. In the exemplary configuration, flanges **44** are spaced and lip **40** defines gaps **52** so that housing **22** may be installed by resting its lower flange **44** behind lip **42** with the upper flanges **44** aligned with gaps **52**. Housing **22** is then pivoted toward plate **28** until its upper flanges **44** are aligned with the channel behind lip **40**. Housing **22** is then slid sideways until at least a portion of the upper flanges **44** are disposed behind lip **40**.

There are alternatives to lock housing **22** in place with respect to base **20**. Flanges **44** may be configured to lock into the channels with snap fitting members. Alternatively, a mechanical connector may be used between housing **22** and base **20**.

In one configuration, gaps **52** are configured to allow housing to be positioned behind lips **40/42** and slid to the right until housing abuts stop flanges **54**. In other configurations, flanges **54** pivot out of the way or are configured to not interfere with housing **22** during the installation of housing **22**.

In the foregoing description, certain terms have been used for brevity, clearness, and understanding. No unnecessary limitations are to be implied therefrom beyond the requirement of the prior art because such terms are used for descriptive purposes and are intended to be broadly construed. Moreover, the description and illustrations provided

herein are examples and the invention is not limited to the exact details shown or described. Throughout the description and claims of this specification the words "comprise" and "include" as well as variations of those words, such as "comprises," "includes," "comprising," and "including" are not intended to exclude additives, components, integers, or steps.

The invention claimed is:

1. A modular lighting assembly, comprising:
a mount having a base and a housing;
the base having a first and second spaced edges that run
in a longitudinal direction of the base; each of the first
and second edges defining a mounting channel;
the housing mountable to the base through engagement
with the mounting channels;
the housing being selectively movable with respect to the
base between a retained closed condition wherein an
interior of the housing is closed by the base and an open
condition wherein the interior of the housing is acces-
sible;
an LED module having a plurality of light emitting
diodes; the LED module being carried by the housing
intermediate the first and second spaced edges of the
base;
a power supply for the LED module electrically con-
nected with the LED module and being disposed inter-
mediate the first and second spaced edges of the base;
and
the power supply having flanges that are disposed in the
mounting channels to mount the power supply to the
base.

2. The assembly of claim 1, wherein a plurality of LED

modules are carried by the housing intermediate the first and
second spaced edges of the base; the plurality of LED
modules being in longitudinal alignment.

3. The assembly of claim 2, wherein the LED modules are

longitudinally spaced apart within the housing.

4. The assembly of claim 1, wherein the housing defines
an opening; the LED module being aligned with the opening
to position the plurality of light emitting diodes in alignment
with the opening.

5. The assembly of claim 4, wherein the housing defines
a plurality of spaced openings aligned in the longitudinal
direction; an LED module having a plurality of light emit-
ting diodes disposed in alignment with each opening.

6. The assembly of claim 5, wherein the power supply is
in longitudinal alignment with the LED modules.

7. The assembly of claim 1, wherein the power supply is
outside of and spaced from the housing.

8. The assembly of claim 1, wherein the power supply is
electrically connected to the LED module with a first
electrical connector that selectively connects the LED mod-
ule to the power supply such that the connection may be
made and remade as desired such that the power supply may
be selectively disconnected from the LED module to allow
for removal and replacement.

9. The assembly of claim 1, wherein the power supply is
carried by the housing.

10. A modular lighting assembly, comprising:

- a mount having a base and a housing;
the base having a first and second spaced edges that run
in a longitudinal direction of the base;

the base defining a first mounting channel along the first
edge of the base;

the base defining a second mounting channel along the
second edge of the base;

the housing including a first flange and a second flange;
the housing being selectively movable with respect to the

base between an open condition wherein the interior of
the housing is accessible and a closed condition
wherein an interior of the housing is closed by the base
when the first flange of the housing is in the first
mounting channel and the second flange of the housing
is not in the second mounting channel;

the housing being retained in the closed condition when
the first flange of the housing is in the first mounting
channel and the second flange of the housing is in the
second mounting channel;

an LED module having a plurality of light emitting
diodes; the LED module being carried by the housing
intermediate the first and second spaced edges of the
base;

a power supply for the LED module electrically con-
nected with the LED module and being located inter-
mediate the first and second spaced edges of the base;
and

the power supply having flanges that extend into the first
and second mounting channels to mount the power
supply to the base.

11. The assembly of claim 10, wherein a plurality of LED
modules are carried by the housing intermediate the first and
second spaced edges of the base; the plurality of LED
modules being in longitudinal alignment.

12. The assembly of claim 11, wherein the LED modules
are longitudinally spaced apart within the housing.

13. The assembly of claim 10, wherein the housing
defines an opening; the LED module being aligned with the
opening to position the plurality of light emitting diodes in
alignment with the opening.

14. The assembly of claim 13, wherein the housing
defines a plurality of spaced openings aligned in the longi-
tudinal direction; an LED module having a plurality of light
emitting diodes disposed in alignment with each opening.

15. The assembly of claim 14, wherein the power supply
is in longitudinal alignment with the LED modules.

16. The assembly of claim 10, wherein the power supply
is outside of and spaced from the housing.

17. The assembly of claim 10, wherein the power supply
is electrically connected to the LED module with a first
electrical connector that selectively connects the LED mod-
ule to the power supply such that the connection may be
made and remade as desired such that the power supply may
be selectively disconnected from the LED module to allow
for removal and replacement.

18. The assembly of claim 10, wherein the power supply
is carried by the housing.

19. The light fixture of claim 10, wherein the second
flange is tapered to frictionally lock in the second mounting
channel.

20. The light fixture of claim 10, wherein the base
includes a stop flange; the housing engaging the stop flange
when the housing is in the closed condition.
